UNITED STATES PATENT OFFICE.

WILLIAM R. JEAVONS, OF CLEVELAND, OHIO, ASSIGNOR TO THE UNITED BLUE FLAME STOVE COMPANY, OF SAME PLACE.

BURNER.

SPECIFICATION forming part of Letters Patent No. 617,291, dated January 3, 1899.

Application filed October 17, 1896. Serial No. 609,220. (No model.)

To all whom it may concern:

Be it known that I, WILLIAM R. JEAVONS, a citizen of the United States, residing at Cleveland, in the county of Cuyahoga and State of Ohio, have invented certain new and useful Improvements in Burners; and I do hereby declare that the following is a full, clear, and exact description of the invention, which will enable others skilled in the art to which it applies to make and use the same.

This invention relates generally to the class of burners in which combustion occurs in a chamber formed by perforated walls, and particularly to the form of burner shown in United States patent to J. A. Lannert and myself, No. 570,854, dated November 3, 1896.

The object of this invention is to provide a simple, safe, and efficient burner for household and other uses and in which by reason of certain novel features of construction a high efficiency is obtained with small consumption of oil.

In the accompanying drawings, Figure 1 is a side elevation of my improved burner. Fig. 2 is a vertical central cross-section thereof on line 2 2, Fig. 1. Fig. 3 is a vertical central cross-section on a line corresponding to 3 3, Fig. 2. Fig. 4 is a plan view looking down from line 4 4, Fig. 3, and disclosing especially the form of the combustion-chambers. Fig. 5 is a perspective view of an adjustable spring-clamp and stop for the valve-stem. Fig. 6 is a plan view of the castings or parts constituting what I term the "vaporizers," and Fig. 7 is an end view of said parts. Fig. 8 is a longitudinal sectional elevation on line 8 8, Figs. 6 and 7. Fig. 9 is a cross-section of the upper member of the vaporizers shown in Figs. 6, 7, and 8 and taken on a line corresponding to line 9 10, Fig. 8; and Fig. 10 is a cross-section of the lower member of the vaporizers on the same line as Fig. 9.

In the several figures, A is the oil-reservoir, which may be of a size to supply two or more burners. The wick-tubes *aa* are secured to the reservoir in any suitable manner and are provided with spur-wheels for operating the wick on spindles *a'* in the usual manner. On each spindle is an adjustable spring-metal clamp C, which turns with the spindle and engages with the stop *c* to limit the movement

of the wick and secured by screw *c'*. In ordinary usage when the clamp C engages the stop *c* the motion of the spindle is arrested; but if by reason of the wick having been trimmed or shortened by burning it requires raising higher than the clamp and stop allow the clamp will yield frictionally on the spindle by the application of something more than the ordinary force to turn it, and in this way the wick can be turned up to any point desired. This new position of the clamp will then become the permanent stopping-place until another kindred change is made. The screw *c'* is therefore used only to primarily give such tension to the spring of the clamp as to produce a desirable grip or friction between the clamping portion and the spindle, and this is its main purpose.

D D are the vaporizers, arranged to rest at or near the top of wick-tubes, and in this case said vaporizers are shaped at their top to form seats for the combustion-tubes E E and have a lateral flange *d* extending from about said seats and forming a bottom for the air-chamber F' within drum or casing F. The two vaporizers, together with the outward flanges *d*, are cast in two pieces—that is, the parts indicated by 1 1 1 1, Fig. 2, are cast in one piece or section and the parts 2 2 *d* in another and separate section. These two sections are then bolted together, as shown in Fig. 3, by bolts and nuts G g.

It is difficult to make a long and narrow walled passage with cast metal, which metal is especially desirable for the vaporizer parts; but by making the vaporizers in two sections, as described, each section carrying one side of the wick-passage, not only is the difficulty of manufacture removed, but the passage-walls are exposed for cleaning and smoothing in the process of manufacture. Then, again, after long use of the burner the sections may be separated to give easy access to all points for cleaning.

The vaporizers rest on and are supported by the wick-tubes at small points of contact at their ends, as shown in Fig. 1 and 3, thus leaving the main portion of the vaporizers out of contact with the wick-tubes. This arrangement practically prevents the downward conduction of heat from the body of the

vaporizers in the operation of the device and the upward crawling of the oil over the burner parts while the burner is idle. A downward projection $d' d'$, Fig. 1, from each 5 end of the vaporizer to engage the ends of the wick-tube secures it against end or side movement, while the transverse downward-projecting web d^2 , which is integral with and carries the two inner walls of the two wick- 10 passages, is made with tapering or rounded edges to extend below the said passages. This web, then, serves as a guide to bring the vaporizer into proper relation to the wick-tubes when being replaced after removal for cleaning, &c. By means of guides, as described, the alinement of the vaporizer-passages with the passages in the wick-tubes is assured, especially as the wick-tubes of this class are flexible to a certain degree and may be crowded 15 by such guides into proper position. Then to give the vaporizer parts stability and to prevent tilting or tipping I provide the tubes or sleeves H, Figs. 2 and 3. The bolts G G, which serve to fasten the sections of the vaporizer together, extend down into the sleeves, as shown, and effectually prevent the vaporizer from tilting. An opening h permits the escape of dirt or foreign matter that may get 20 into the tube H.

30 Above the vaporizer is the frame J, hinged thereto by loose hinge j and providing a seat for the drum or casing F. Bolts K K connect frame J and casting k, which surmounts drum F, and serve to bind said parts together upon 35 said drum, said parts forming an air-chamber F' about the combustion-tubes. The top casting or plate K projects over this air-chamber to partially close it and leaves a contracted opening adjacent to the outer side 40 of each combustion-tube, through which heated air from the chamber F' may pass to the flame issuing from the combustion-tubes. The plate K is also provided with a central portion L on a somewhat lower plane, which 45 rests between the two combustion-tubes, Figs. 2 and 3, and serves to retard the upward flow of air. This portion L is somewhat narrower than the space between the two tubes to permit some air to pass by it, and at its ends 50 where it connects with the main plate K it is made quite narrow to permit a larger volume of air to pass out adjacent to the ends of the combustion-tubes. By this arrangement the air supplied to the chamber above L passes 55 in close proximity to the perforated walls and tends to exert a cooling influence on said walls at this point, which not only contributes to a greater durability of the parts, but furnishes more favorable conditions within 60 the combustion-chamber for the evolution and combustion of the gases. This plate L, instead of being narrow to pass air at its sides, may be wider and have openings through it for the passage of air.

65 The combustion-tubes E E are supported by a rod M, which passes through holes in the casing F and the said tubes and extends

through from side to side of said parts. This rod has one end bent to rest against the side of the casing and is retained in place by 70 means of the overhanging cleat or catch m, which engages said bent portion.

The holes in the combustion-tubes for the rod M are so arranged that when the tubes are seated in the vaporizer the frame J is 75 supported a slight distance above the flange d. This in effect brings the weight of the frame-casing and upper parts on the combustion-tubes to hold them firmly in their seats. The combustion-tubes being supported centrally on rod M have a slight rocking movement and may adjust themselves to any inequalities in the seats, which conditions might arise by dirt accumulation or other causes. In this form of burner it is also desirable to maintain a proper spacing of the walls of the combustion-chamber, and hence to guard against warpage by unequal heating, &c., the spacers e e are provided. These spacers are of heavy sheet metal and are 85 formed with a shoulder and a projection or tongue at each end. Suitable holes are made in the opposite sides of the chamber for the passage of these tongues. The chamber-walls may be temporarily sprung wide enough 90 to permit their insertion, after which the portion of the tongues projecting through the walls is clenched.

At the top of the combustion-tubes is the web or cap N, which spans over the space between the two tubes. This cap has a number of holes for the passage of air and also has a portion at its ends cut away at n', Figs. 1 and 3, to pass a greater volume of air through at these points. The partition L in 105 the space below this web or cap N restricts and modifies the flow of air passing through the interior of the burner, and the cap serves to distribute this restricted volume of air, as described.

The inner wall of each combustion-tube is bent at its top to form a groove with a lateral opening. The cap N is formed with inwardly-projecting flanges adapted to slide into these grooves, which arrangement, while permitting the combustion-tubes to move sufficiently on the rod to adjust themselves to their seats, closes the joints against the lateral passage of air. Below the cap N the inner wall of the combustion-tube is imperforate for a 110 short distance, as shown in Figs. 2 and 3. This seems to induce an increased combustion at the perforations in the other wall opposite this point and lengthens and improves the character of the flame issuing from the 115 tube.

In Fig. 2 it will also be observed that the inner walls of the combustion-tubes have fewer perforations than the outer wall.

Ordinarily with tubes perforated alike a 120 relatively greater volume of air passes through the upper perforations of the inner tube than through the lower ones. With the inner tube having less perforations or a rela-

tively less inlet area than the outer tube a more generally uniform inflow of air occurs throughout all the perforations of the inner tube, and thus the tube does not become so excessively heated at certain points, but such heat is distributed throughout the tube, which contributes to more uniform temperature about the wick and imparts a more desirable character to the flame, and such uniform heating contributes to the durability of the parts. The physical or chemical action on the gases induced by the unequal perforations on opposite sides of the chamber may not be thoroughly understood by me. It is thought, however, that such differing walls induce differing chemical action, as well as a differing physical movement of the gases evolving in the chamber from what occurs where the walls are perforated alike, and that the increased difference in temperature of the outer and inner wall, caused primarily by the differing perforations, greatly favors the conversion of vapor into carbonic acid, and the unequal air-supply together with the unequal heating of the gases, induces in them a physical motion that tends to more intimate mixture and uniformity. In combustion-chambers of this class where a flat wick is used it is desirable to supply less air to the ends than to the sides of the flame within the chamber. To this end each combustion-chamber is made in two pieces, the end of one piece being bent sufficiently to serve as a spacer for the other wall, while the end of the other wall laps around the first bent wall to make two thicknesses about the end. In practice this arrangement is found to diminish the supply of air through the ends of the tube so formed, as by reason of a non-alinement of the perforations in the two pieces, and even where some do happen to aline, less air passes through the two thicknesses than would through one thickness by reason of greater resistance in the longer passage. Also by this method oflapping one wall over the other the two walls are held in proper relation without other special means of fastening. The outer wall of each combustion-tube is flared outwardly at e' , as shown in Fig. 2. This flared portion, by reason of its tendency to induce an eddy or partial vacuum immediately above it, causes the flame to spread out wider as it issues from the combustion-chamber than it would do if the flared portion were not there.

What I claim as new, and desire to secure by Letters Patent, is—

1. In the burner described, the wick-tube, the vaporizer having a wick-passage and provided with projections engaging said wick-tube, and serving to keep the wick-passage in alinement with the said tube, substantially as described.

2. The wick-tube, and the vaporizer having a passage for the wick and projections adapted to guide the vaporizer to its position above said tube, substantially as described.

3. The wick-tubes, the vaporizer having a projection at its bottom, and an upwardly-projecting part engaged by said projection, 70 said engaging parts constructed to prevent tilting of the vaporizer, substantially as described.

4. The vaporizer provided with a seat for the combustion-tube, and having one side of 75 the wick-passage therein cast integral therewith, and the other side of the said passage cast in a separate section, and burner parts connected with said vaporizer, substantially as described. 80

5. The wick-tube, the combustion-tube over the wick-tube and a seat for supporting the same, a pivot-rod projecting through the combustion-tube and a casing supported by said rod in movable relation to said combustion- 85 tube, substantially as described.

6. In a vapor-burner, the perforated combustion-tubes arranged in proximity to each other and side by side, with a space between them, and an air-checking plate or partition 90 in said space constructed to permit of an upward flow of air at its margin and in position to direct the passing air against the sides of the combustion-tubes, substantially as described. 95

7. In a vapor-burner, the perforated combustion-tubes arranged in proximity to each other and side by side, with a space between them and an air-checking plate or partition in said space, a casing forming an air-chamber 100 about said tubes and supporting the said air-checking plate in position, substantially as described.

8. In a vapor-burner the perforated combustion-tubes arranged side by side with a 105 space between them, a casing about said tubes provided with a plate having a central portion extending into said space to steady and space the said combustion-tubes laterally, substantially as described. 110

9. In a vapor-burner two combustion-tubes having substantially parallel perforated sides arranged in proximity to each other with a space between and a plate at the upper portion of said tubes having a central portion 115 extending into said space to form an air-checking partition and adapted to steady the said tubes against lateral displacement, substantially as described.

10. In a burner two perforated tubes in proximity to each other with an air-space between them, a web or cap extending from one tube to the other, and a partition in the space below said cap constructed to permit of an upward flow of air at its margin and forming 120 with said cap an air-chamber between the upper ends of the combustion-tubes, substantially as described. 125

11. In a burner, two perforated combustion-tubes in proximity to each other and having 130 an air-space between them, a web or cap extending from one tube to the other over said space, and a partition in the said space below said cap and forming with it an air-chamber

at the upper ends of the combustion-tubes, said air-chamber having an opening at its bottom to permit a limited volume of air to pass into said chamber, and an opening at the 5 ends of said cap for the escape of air from said chamber, substantially as described.

12. Two combustion-tubes arranged in proximity to each other and the inner wall of each tube, respectively, provided with a 10 lateral groove, and the cap having flanges to engage said grooves to hold it in position, substantially as described.

13. Two perforated combustion-tubes arranged side by side and having an air-space 15 between them, a web or cap spanning said space, and outlets at the ends of the cap for the passage of air from the said space between the combustion-tubes, substantially as described.

14. In a burner, two perforated walls forming opposite sides of a combustion-chamber, the perforated area of one wall having relatively less opening area than a like perforated area of the other wall, a similar combustion-chamber arranged in proximity and having 25 its perforated walls in symmetrical correspondence to said first-described combustion-chamber and forming therewith an air-chamber centrally within the burner, substantially 30 as described.

15. A combustion-tube formed of two walls perforated from end to end, the end of one wall bent to form a stay for the other wall and the said other wall having its end formed 35 to embrace said stay, substantially as described.

16. In a vapor-burner, two combustion-tubes arranged in proximity to each other, the perforated area of the inner walls of the 40 said combustion-tubes having a relatively less opening area than a like perforated area of the outer walls of said tubes, substantially as described.

17. In a vapor-burner two combustion-tubes arranged in proximity to each other, the perforated area of the inner walls having a relatively less opening area than a like perforated area of the outer walls, and an imperforate area at the upper end of the said 50 inner walls, substantially as described.

18. In a burner, a wick-tube, an outside casing, a perforated combustion-tube within said casing and pivotally supporting said casing, and means for supporting the combustion-tube above the wick-tube, substantially 55 as described.

19. In a vapor-burner the combination of a combustion chamber or chambers composed of perforated walls constructed and arranged 60 to form opposite sides of a burner and having an air-chamber in the interior thereof and the inner perforated wall or walls having relatively less opening area than a like perforated

area of the outer wall or walls, substantially as described.

20. In a vapor-burner, the combination of a combustion chamber or chambers composed of inner and outer perforated walls constructed and arranged to form opposite sides of a burner and having an air-chamber in the 70 interior thereof and one perforated wall or set of perforated walls constructed so as to admit more air into the combustion-chamber than is admissible through the other perforated wall or set of perforated walls, substantially 75 as described.

21. In a vapor-burner, the combination of a combustion chamber or chambers composed of inner and outer perforated walls constructed and arranged to form opposite sides of a burner and having an air-chamber in the 80 interior thereof and one perforated wall or set of perforated walls constructed so as to admit more air into the combustion-chamber than is admissible through the other perforated 85 wall or set of perforated walls and one of said walls or sets of walls imperforate at the upper end or ends, substantially as described.

22. In a vapor-burner the combination of a combustion chamber or chambers composed 90 of perforated walls constructed and arranged to form opposite sides of a burner and having an air-chamber in the interior thereof, a plate or partition situated within said air-chamber and constructed and arranged to provide air-passages between it and the inner wall or walls 95 of the combustion chamber or chambers, said plate or partition adapted to restrict the flow of air to the upper part of the air-chamber and to deflect a portion of the air through the 100 perforations of said inner wall or walls below said plate or partition, substantially as described.

23. In a vapor-burner the combination of a combustion chamber or chambers composed 105 of perforated walls constructed and arranged to form opposite sides of a burner and having an air-chamber in the interior thereof, a web or cap over said air-chamber, a plate or partition situated within said air-chamber below 110 said cap and constructed and arranged to provide an air passage or passages between it and the inner wall or walls of the combustion chamber or chambers, said plate or partition adapted to restrict the flow of air to the upper 115 part of the air-chamber and to deflect a portion of the air through the perforations of the inner wall or walls below said plate or partition, substantially as described.

Witness my hand to the foregoing specification this 10th day of October, 1896.
